UNITED STATES PATENT OFFICE.

GEORGE H. BARBOUR, OF PITTSBURGH, PENNSYLVANIA.

RAIL-JOINT.

1,348,345.

Specification of Letters Patent.

Patented Aug. 3, 1920.

Application filed December 6, 1917. Serial No. 205,710.

To all whom it may concern:

Be it known that I, GEORGE H. BARBOUR, residing at Pittsburgh, in the county of Allegheny and State of Pennsylvania, have 5 invented a new and useful Improvement in Rail-Joints, of which the following is a full, clear, and exact description, reference being had to the accompanying drawings, forming part of this specification, in which:

10 Figure 1 is a sectional elevation of a portion of a railway track embodying my invention;

Fig. 2 is a vertical cross-section of the structure shown in Fig. 1;

15 Fig. 3 is a perspective view of a slightly modified form of one of the joint bars which I preferably employ.

20 My invention has relation to rail joints, and is designed to provide a rail joint having a novel form of splice bar which is so constructed as to permit the joint portions of the rails to have some vertical movement between their points of support on the bars.

The present application is a continuation 25 in part of my copending application Serial No. 88,817 filed April 4, 1916, and of my Patent No. 1,252,647, dated January 8th, 1918.

30 The nature of my invention will be best understood by reference to the accompanying drawings, which will now be described, it being premised, however, that the invention is susceptible of other modifications within the scope of the appended claims.

35 Referring to these drawings, the numeral 2 designates track rails, and 3 the joint bars. The particular form of joint which I have shown, is, in general, similar to that described and claimed in my said application, Patent No. 1,252,647 of January 8, 1918, being a riveted joint employing tubular rivets which are seated and expanded while the engaged parts are held under compression in the manner more fully described in said application. The splice bars illustrated are, 40 however, of somewhat different form than those shown in my said application. Each of these bars comprises an upper flange 4, a lower flange 5, and a connecting vertical web 6, the spaces between the two flanges forming 45 seats for the heads of the rivets. These splice bars also preferably have limited areas of contact with the fishing angles of the rails, being provided for this purpose with spaced bearing projections 7, which 50 engage the fishing angles. The purpose of

these limited areas of contact will herein-after appear.

The tie shown in Figs. 1 and 2 consists of an integral rolled metal section having a generally horizontal, although preferably somewhat V-shaped web portion 8; downwardly and outwardly sloping ballast-bearing flanges 9, terminating in horizontally extending and preferably thickened edge portions 10, and two right-angled rail-carrying flanges 11, one of which rises at each juncture of the web 8 with one of the flanges 9. The rail-supporting portions of the right-angled flanges 11 are turned horizontally outward and are preferably thickened, as indicated at 11^a. This thickening of these flanges, as well as the thickening of the edge portions 10 of the flanges 9, materially stiffens and increases the strength of the ties.

75 The rails 2 are secured to the ties by any suitable fastenings. In the drawings, I have shown the tie plates 12, secured to the flange members 11^a of the ties by rivets 13 and having rail-base-engaging clips 14 and 15. The clip 14 is shown as integral with the tie plate, while the clip 15 is a separate member which is secured by one of the rivets 13.

80 It will be noted that the ballast-bearing area of each tie is formed not only by the flanges 9 and 10, but also by the webs 8, thereby giving a relatively large total ballast-bearing area. Also that the sloping arrangement of the flanges 9, together with 85 the V-shape of the web 8, gives the tie a self-tamping action.

85 Rail joints constitute a great defect in track construction. In the joints heretofore employed fourteen inches more or less of the rail ends are held rigidly in a vise-like manner between the splice bars, and these portions of the rails are thereby prevented from deflecting freely. By the use 90 of splice bars of the character hereinbefore described, having spaced apart bearing projections 7, engaging the fishing angles of the rails, this vise-like grasp is in part relieved and the rail is permitted some vertical movement between its points of support on the bars. Splice bars embodying this feature may be of widely different forms, one of such forms being shown in Fig. 1 and a somewhat modified form in Fig. 3. It will be noted that with the form 95 11

of bars shown, the bottom flanges of the bars will entirely clear the fastenings which secure the rails to the ties.

I claim:

5. 1. A joint plate or splice-bar for railway track rails, comprising a web having upper and lower projecting portions on its inner side, said portions having non-continuous rail bearing projections, substantially as de- 25
scribed.
10. 2. A joint plate or splice bar for railway track rails, comprising a web having upper and lower projecting portions on its inner side, said portions being intermittently 15 thickened along their free edges to provide non-continuous rail bearings, substantially as described.
15. 3. A joint or splice bar for railway track rails, comprising a web having flanges ex- 20
tending from its upper and lower edges and

having central and end rail-bearing projections at both its upper and lower edges, the lower flange of said bar being constructed to form a covering for the cross-tie fastening means of the rail, substantially as de- 25
scribed.

4. A rail joint having opposite splice bars embracing and secured to the end portion of the rails, each of said bars comprising a web having flanges extending from the upper 30 and lower edges thereof, said bars having intermittent rail-bearing projections at both their upper and lower edges, the lower edge of said flanges having a thickened extremity arranged to clear and cover the cross-tie 35
fastening of the rail, substantially as de-
scribed.

In testimony whereof, I have hereunto set my hand.

GEORGE H. BARBOUR
